FOLDING TABLE

Frank Peck, Colorado Springs, Colo.

Application July 27, 1933, Serial No. 682,445

4 Claims. (Cl. 311—67)

This invention relates to folding tables, its primary object being to provide a table which when not in use may be folded so compactly that, with reference to its normal extent, it will occupy a comparatively very small space.

A further object of the invention is to provide a foldable or collapsible structure which may be adjusted to provide tables of different superficial dimensions, and still other objects reside in novel constructions and in novel combinations and arrangements of parts, by which simplicity of construction is combined with strength, stability, and practicability in use.

An embodiment of my invention has been shown in the accompanying drawings in the several views of which, like parts are similarly designated and in which,

Figure 1 is a partially broken plan view of the table.

Figure 2, a partially sectional side elevation of the same.

Figure 3, a transverse vertical section of the upper portion of table taken on the line 3—3 of Figure 1.

Figure 4, a sectional view showing a modification in which the table top is permanently connected to the supporting frame, the top being in its normal horizontal position.

Figure 5, a similar view showing the top in a suspended position when the structure is in a folded or collapsed condition.

Figure 6 is a perspective view of the leg-supported folding frame of the table.

Figure 7, a perspective view of the frame in a partially collapsed condition.

Figure 8, a perspective view of the frame in its complete folded condition, and

Figure 9, a perspective view of a portion of a table made in accordance with the modification illustrated in Figures 4 and 5.

Referring further to the drawings, the table as shown in Figures 1 to 3 and 6 to 8, comprises three separate elements, namely; a folding supporting frame A, a folding top B, and a folding brace C.

The folding top is composed of two sections 5, each having two leaves 6 hinged together as at 7; and each having at its underside lengthwise and transversely extending cleats 8 and 9, which fit inside the frame as will hereinafter be described, and thereby stabilize the structure in its assembled state.

The table sections have at their abutting ends dowel-pins 21 and correspondingly formed sockets 22 fitting one within the other.

The supporting frame comprises legs 10 rigidly connected in pairs by transverse frame-rails 12. The pairs of connected legs, which constitute the ends of the supporting structure, are connected by side rails, each composed of hingedly connected normally aligned members 13, 14 and 15. The members 15 are in the form of studs which are rigidly connected to the ends of the supporting structure at diagonally opposite points thereof.

The members 13 and 14 of the side rails are 10 jointed at abutting ends by hinges 16, and they are foldably connected at their outer ends, directly to one of the ends of the structure and to the stud of the opposite end of the same, respectively, as by means of hinges 17 and 18. 15

The hinges 18 which connect the members 14 of the side rails to the studs 15 have angular extensions which embrace the adjacent legs of the ends of the support, for the purpose of connecting the studs to the legs, in a manner which reinforces the structure, and the hinges 17 have similar extensions also for the purpose of reinforcement.

The brace-element of the table comprises two members 19 and 20 centrally pivoted together as 25 at 23. The longitudinal member 19 is notched at its ends to fit in seats 24, fastened centrally of and upon the inside of the end rails 12, and the transverse member 20 fits between the side rails of the frame, when the members are at 30 right angles to each other.

The brace-element thus holds the side rails against accidental collapse, when the supporting structure is in its normal, extended condition shown in Figures 1, 2, and 6. 35

The top of the table, in its normal condition, is placed upon the supporting structure with its cleats 8 and 9 in engagement with the end-rails and the side-rails respectively, so that it is rigidly held against displacement. 40

The elements of the table thus assembled, provide a structure so stable and rigid as to favorably compare with a table of the usual solid form.

When the table is not in use, its top-sections are lifted off the supporting frame and placed together in a folded condition, thereby occupying but little space. The brace-element is removed from the supporting frame, and its members are placed in alinement by turning one about its pivot with relation to the other. 45

Finally the supporting frame is collapsed by moving the members 13 and 14 of the side rails inwardly, about the hinges 16, 17 and 18, which 50 55

connect them to each other and to the end parts of the frame.

Owing to the provision of the diagonally opposite studs 15, the pairs of connected members of the side rails may be folded past each other as clearly shown in Figure 7 until they extend in parallel relation to each other and to the end rails as shown in Figure 8.

It follows that the length of the side-members of the frame is not restricted by the length of the end-members of the same, so that while the frame in its collapsed condition is compact to the extreme, it is in its extended state, sufficiently long to support a top of a length suitable 10 for use as a large dining room table, or as a library or director's-room table.

The table may be further extended by joining two or more frames of the character hereinbefore described in end-to-end relation and correspondingly increasing the number of sections of which the top is composed.

This feature of the invention is so obvious that it has not been thought necessary to illustrate the same.

26 Instead of providing a top which is removable, relative to the supporting structure, one or both of its sections 6a may be permanently connected to the end-sections of the structure as illustrated in Figures 4, 5 and 9 of the drawings. The connections between the top 5a and the supporting frame are established by means of hinges 25 which are of composite construction, so that the top sections may be lifted and turned over and around the rails 12a of the respective ends of the frame and then lowered in a folded condition to hang parallel to and outside the ends as shown in Figure 5. The frame in this modification comprises legs 10a rigidly connected in pairs by transverse frame rails 12a. The pairs of connected legs, which constitute the ends of the supporting structure, are connected by side rails, each composed of hingedly connected normally alined members 13a, 14a and 15a. It will be understood that the top and frame are identical 35 with the corresponding parts illustrated in Figure 1, except as otherwise noted. In the construction shown the hinges 25 are each composed of five blades hinged together, the outer blades being fastened inside the end rails and under the top, respectively. It will be understood that one or more of these hinges may be applied at one or both ends of the frame.

50 One advantage of the last described modification is that the brace-element of the first de-

scribed form of the invention may be dispensed with, since the top-sections, permanently connected at the ends of the supporting frame and abutting one another in end-to-end relation, will hold the frame against collapse.

5 Another advantageous feature of the modified construction is that the top-sections may be placed in a folded condition upon the supporting frame in a totally or partially collapsed condition, to provide a table of smaller dimensions.

10 Thus a table made according to the present invention may be used as a dining room table or a library table, or it may be reduced in size for use as a card table or as a side table. The last mentioned use has been illustrated in Figure 9, in which one section of the table is shown in a suspended position, while the other section in a folded condition rests upon the supporting frame.

15 The table has been shown as placed against a wall 26 of the room.

Other modifications of the invention may be resorted to within the scope of the hereunto appended claims.

20 What I claim and desire to secure by Letters Patent is:

1. A table comprising a frame having supporting ends and folding side-rails connecting said ends, a brace-element composed of two members, one of which extends between the ends, and another of which extends between the side-rails, and a top resting on the frame.

25 2. A table comprising a frame having supporting ends and folding side-rails connecting said ends, a brace-element composed of two pivotally connected members one of which extends between the ends, and another of which extends between the side-rails, and a top resting on the frame.

30 3. A table comprising a frame having supporting ends and folding side-rails connecting said ends, a brace-element composed of two members, one of which is seated upon the ends, and another of which extends between the side-rails, and a top resting on the frame.

35 4. A table comprising a frame having supporting ends, side-rails connecting said ends, each side-rail comprising a stud fastened to an end-member, a member hinged to the stud, and a second member hinged to the first-mentioned member and having its opposite end hinged to an end-member, the studs of the respective side-rails being at diagonally opposite points of the frame, and a top resting on the frame.
